EXHAUST PIPE AND PIT

Application filed March 7, 1927. Serial No. 173,588.

My invention relates to gas engine exhaust receivers and more particularly to exhaust pit equipment for restraining and reducing the explosibility of the gases exhausted by an engine.

My object is to provide improvements in exhaust-disposal equipment whereby the exhaust gases will be more thoroughly mixed and longer restrained for substantial reduction of the hazards of spark emission and explosion.

In oil field practice pipes laid preferably in trenches conduct exhaust gases from an internal combustion engine to a distance for discharge so that the exhaust products may not constitute a fire hazard adjacent the working scene, the products discharging into a muffler and the arrangement meeting the additional well-known purposes of means for dissipating such exhaust gases. The hazard is not entirely removed, however, by the conventional installations, since a mis-fire of the engine may result in the passage of an unconsumed charge of gas to the muffler, where the charge may explode and project a flame into the atmosphere to constitute a serious hazard.

I provide for the accomplishment of my object, means to overcome the conditions that may cause danger, comprising a housing receiving the exhaust gas conducted to a distance from the engine, the housing having an inlet introduced tangentially so that the entering exhaust gases are given a swirling movement, a conical roof and a vertical outlet therein, whereby the gases are restrained and thoroughly mixed and the liability of explosion practically eliminated.

These and other elements of structure and function will be particularly described with references to the accompanying drawings, in which:

Fig. 1 is a side elevational view of my device and of an engine that it serves.

Fig. 2 is a perspective view of the muffler element.

Fig. 3 is a cross section of the muffler on the line 3—3, Fig. 1.

Fig. 4 is a detailed view in perspective of pipe-connecting means.

Referring in detail to the drawings:

1 designates generically an internal combustion engine, 2 a conduit conducting the exhaust gases from the engine to a cylindrical housing or muffler 3, and 4 a trench or elongated pit accommodating the muffler and conduit. The conduit, connected to the exhaust port of the engine at 5, comprises a plurality of pipes 6, one of which, designated 7, is shown as curved on a relatively long radius to provide as free and unobstructed movement as possible for the gases into a deflected course.

The housing 3 comprises upper and lower body portions or rings 8 and 9, having flanges 10, the bottom plate 11 projecting to coincide peripherally with the flange of lower ring 9 and the conical top 12 having a flange 13; adjacent parts being secured together by bolts 14. Two rings are shown, suggesting extensibility. The conical top 12 is provided with an axial flanged outlet 15 to which a flanged exhaust outlet pipe 16 may be attached having an axis aligned with the axes of the top and chamber.

The lower ring or body portion 9, shown in plan view in Fig. 3, is provided with a feature that constitutes an important element of my invention, namely, a tangentially disposed exhaust inlet member 17. The inlet member is preferably constructed as an integral straight pipe portion of the ring 9, and installed adjacent the lower end of the ring, in a plane at right angles to its axis, and having a longitudinal line of its interior surface in its horizontal diameter coincident with a line tangent to the inner periphery of the ring, the inner end of the inlet registering with the inner periphery of the ring. The connection of the conduit 2 with said inlet will later be particularly described.

The construction as shown provides that the exhaust gases projected through the conduit will enter the housing near its lower end, and traveling horizontally on chords of the housing less than the diameter thereof, impinge against the inner housing wall at obtuse angles. The stream of gases therefore is deflected into a circular course parallel

to the horizontal bottom plate of the housing, and tends to maintain such course and to circulate therein. The gases are restrained therefore in the lower part of the housing for an appreciable and relatively substantial period so that incoming portions are caused to mingle and become entangled with portions previously received. The departure of the gas upwardly through the housing and from the outlet is considerably delayed and the commotion produced by the eventual diversion of the portions of gases towards the outlet on different spirals and helices of short pitch effect a thorough commingling of the gases of various degrees of leanness and richness. It therefore occurs that a chance unconsumed charge of gas or any portion of live gas, that may be admitted to the housing is so completely mixed with the dead gases therein, that no portion of gas leaving the housing is of sufficient richness to combine with the air and cause an explosion even though a spark may be present. The conductance of the exhaust gases over a substantial distance substantially reduces the possibility of a spark persisting in the gas stream to the housing.

I provide also explosion doors such as closing a relief opening in the conical roof having hinges 19 and disruptable latching means such as the frangible wooden pin 20 engaging the hasp 21 with a loop 22 fixed in the roof, the pin designed to break under impact of an explosion to permit the force to relieve itself and prevent damage to any part of the structure.

My device is particularly useful in oil fields where sparks from the exhaust of a gasoline engine operating near a well may ignite gas escaping from the well.

That I may assure the conductance of the gases to my improved exhaust pit equipment for eradication of explosion hazard as described, I provide a special means of connecting the pipes 6 to prevent leakage of gases from the conduit, comprising the insertion of heat-resistant gaskets in the joints, and structure that will promote the efficiency of the sealing and also permit a certain amount of flexibility in the contour of the pipe line. A pipe 6 is provided with an annular arcuate rib 23 adjacent one end and a beveled end portion 24 tapering from the exterior edge of the rib to the end of the pipe; and a bell flange 25 at its other end having a beveled recess 26 to receive the beveled portion 24 of another pipe, and a square socket 27 having the lip 28 of the bell flange as one side thereof to receive an asbestos or similar heat-resistant gasket 29. A gasket is seated on the arcuate rib of a pipe, and the bell flange of another pipe is positioned over the ribbed end of the first named pipe as suggested. Ears 30 preferably two in number are pro-

vided integral with a pipe, and at each end thereof, having orifices 31 through which bolts 32 may be inserted to join adjacent ears of pipes brought together and by compression tightly seal the joints. The construction as shown provides a self-aligning seat for the bell flange, so that the pipes may be laid on irregular ground without requirement of exact alignment, the joints retaining their sealing character and leakage being avoided.

The pipe line comprised of pipes 6 is preferably connected with the inlet 17 by means of an expansion joint 33, to provide for expansion and contraction of the unflanged end of the pipe inserted into the inlet and comprising the inlet collar 34 and the gland sleeve 35 having the gland 36 engaged with the collar, the sleeve being secured to the collar by bolts 37, and packing 38 being provided.

What I claim and desire to secure by Letters Patent is:—

1. An exhaust pipe and pit comprising a vertically positioned cylindrical body providing an unobstructed vertical cylindrical chamber having a conical outlet at its upper end coaxial with said chamber, and a horizontal inlet pipe introduced tangentially to the body at its lower end having an inner end registering with the inner periphery of the body for causing movement of inlet gases in an unobstructed horizontal circular path and permitting upward flow of said gases in unobstructed spiral paths toward the outlet.

2. In a device of the character described, an exhaust pit comprising a cylindrical housing having an inlet at its lower end, a conical cover having an apical outlet and a relief opening, a door closing the opening, and a frangible latch for the door adapted to be disrupted under impact of explosion in the pit.

3. In an exhaust pipe and pit, a housing having an inlet at its lower end, a conical cover having an outlet and a relief opening, a door hinged to the cover to close the opening, and means disruptable under impact of an explosion occurring within the housing for latching the door in closed position.

4. An exhaust pit including a ring providing an unobstructed vertical cylindrical chamber and having a horizontal bottom wall, an inlet tangential to the chamber adjacent the lower end of the ring and having an axis parallel with said bottom wall, the inner end of the inlet registering with the inner periphery of the ring, and a conical top member having an apical outlet coaxial with the chamber.

5. An exhaust pit comprising a ring forming an unobstructed cylindrical chamber, a transverse wall at one end of the chamber having an unobstructed surface perpendicular to the axis of the chamber, an inlet introduced tangentially to the chamber adjacent

said wall surface, the inner end of the inlet registering with the inner periphery of the ring, and a conical outlet at the other end of said chamber having an inlet end concentric with the outlet end of the chamber.

5 In testimony whereof I affix my signature.
